(57) **CLAIM**

The ornamental design for a solid state lighting apparatus, as shown and described.

DESCRIPTION

FIG. 1 is a top perspective view of a solid state lighting apparatus showing our design;

FIG. 2 is a top view thereof;

FIG. 3 is a bottom view wherein the broken line showing of the lens and top surface of the chips have been omitted for ease of illustration thereof;

FIG. 4 is a side view thereof;

FIG. 5 is an opposing side view thereof;

FIG. 6 is front view thereof; and,

FIG. 7 is a back view thereof.

The broken lines shown herein are for illustrative purposes only and form no part of the claimed design.

It is certified that error appears in the above-identified patent and that said Letters Patent is hereby corrected as shown below:

On Title Page:

Under DESCRIPTION, Line 3: Please replace FIG. 2 to read as follows:

-- FIG. 2 is a top view wherein the broken line showing of the lens and top surface of the chips have been omitted for ease of illustration thereof; --

Line 4, FIG. 3: Please replace FIG. 3 to read as follows:

-- FIG. 3 is a bottom view thereof; --

Signed and Sealed this
Sixth Day of January, 2015

Michelle K. Lee
Deputy Director of the United States Patent and Trademark Office
